UNITED STATES PATENT OFFICE.

BENJAMIN A. HARRIS, OF LONE WOLF, OKLAHOMA.

SIGN-EXHIBITOR.

983,708.

Specification of Letters Patent. Patented Feb. 7, 1911.

Application filed June 26, 1908. Serial No. 440,557.

To all whom it may concern:

Be it known that I, BENJAMIN A. HARRIS, a citizen of the United States, residing at Lone Wolf, in the county of Kiowa and 5 State of Oklahoma, have invented new and useful Improvements in Sign-Exhibitors, of which the following is a specification.

My invention relates to improvements in sign exhibitors, and the primary object is 10 the provision of an exhibitor in the use of which a sign of water proof paper or other material may be displayed along streets, roads, and railways, the invention comprehending an exhibitor which may readily 15 and quickly be attached to a fence, post, tree, wall or other support.

A further object of the invention is the provision of a sign exhibitor which is adapted to prevent the sign from being torn or 20 otherwise injured by the wind.

A still further object of the invention is the provision of a sign exhibitor which is simple, durable and efficient and which may be manufactured and sold at a comparatively 25 low cost.

With the above and other objects in view the invention consists in the construction, combination and arrangement of parts hereinafter fully described and claimed, and 30 illustrated in the accompanying drawings, wherein—

Figure 1 is a view in front elevation of a sign exhibitor constructed in accordance with my invention, and Fig. 2 is a plan view 35 illustrating the construction of the members of the exhibitor, the members being shown in spread relation.

My improved sign exhibitor comprises 40 duplicate members A and B which are adapted to support between them the sign C, of water proof paper or other material. Each member of the exhibitor comprises 45 a rectangular frame 2 which is preferably constructed of a single length of stout wire, and a reticulated panel 3. The panels 3 are formed of transverse wires 4 which are secured at their ends to the sides of the frames 2 and longitudinal wires 5 which are interlaced with the wires 4 and which are secured 50 at their ends to the ends of the frames 2. The members A and B are secured together in exhibitor form by means of loops 6 which embrace the ends and the lower

sides of the frames of the members, this manner of securing the members together 55 providing a sign receptacle open at its upper side.

In practice the sign is inserted into the receptacle, that is to say between the members of the exhibitor through the open side 60 thereof, after which the opened side is closed by means of loops 7 which embrace the top sides of the frames of the members. The exhibitor may be secured to a post, wall, tree or other suitable support. The exhibitor is especially adapted to be secured 65 to a wire fence by means of loops 8 and which are passed about the upper and lower sides of the frames of the members and about the adjacent line wires of the fence, 70 as clearly illustrated in Fig. 1 of the drawings. The loops 8 not only provide means by which the exhibitor may be secured between two line wires of a fence, but also assist in securing the members of the exhibitor 75 together. The panels 3 engage and support the sign member and prevent it from being torn or otherwise injured by the wind.

It should be apparent, from the above description, taken in connection with the 80 accompanying drawings, that I provide a sign exhibitor which may be readily and quickly secured to any suitable support, which is adapted to protect the sign from injury by the wind and which can be manufactured and sold at a comparatively low 85 cost. It should also be apparent that the sign is plainly visible through the exhibitor and that the exhibitor is simple, durable and efficient. 90

Changes in the form, proportions and minor details of construction may be made within the scope of the claim without departing from the spirit or sacrificing any of the advantages of the invention. 95

Having thus described the invention what is claimed as new is:—

A sign exhibitor comprising duplicate members between which is supported a sign, each member consisting of a rectangular frame of stout wire, and a reticulated panel 100 of interlaced wires secured at its edges to the sides and ends of the frame, loops embracing the sides and ends of the frames to secure the members together, the panels 105 engaging and supporting the sign and pre-

venting it from being torn or otherwise injured by the wind, and other loops embracing the sides of the frames and providing means by which the exhibitor may be secured to and between two line wires of a fence, said other loops also assisting in securing the members together.

In testimony whereof I affix my signature in presence of two witnesses.

BENJAMIN A. HARRIS.
